CONVEYER GUARD

William J. E. S. Seigh and Delton J. Du Chene,
Monroe, Mich.

Application October 16, 1948, Serial No. 54,864

6 Claims. (Cl. 104—133)

1

This invention relates to conveyor guards and is particularly directed to a structure suitable for use with conveyors of the rail type in which conveyed parts are carried suspended from a track or runner.

At the present time, regulations covering the installation of conveyors in many States require that wherever articles are carried in a suspended condition over a working area, a suitable continuous guard must be provided to protect against the elevated articles falling from the conveyor. In compliance with such regulations it has been proposed to utilize what amounts to a continuous basket of expanded metal or the like placed in position to catch any objects that may become accidentally dislodged from the conveyor in its travel. The supports for such devices have been welded or otherwise permanently fixed to the conveyor frame or rail and sections of the devices have, in the past, been similarly permanently fastened together. Such structural permanence makes it very difficult to change conveyor routings or in any other way to alter any existing installation. The present invention completely obviates this and many other disadvantages of known structures.

The primary object of the invention is to provide a conveyor guard which is easily demountable but which may be assembled with sufficient permanence to provide complete safety for the installation.

Another object of the invention is to provide a conveyor guard in which assembled structural shapes may be used for bracing elements and in which provision is made for fastening such bracing elements to the conveyor by simple bolts and nuts for ready removability.

Another object of the invention is to provide a conveyor guard in which the guard may be readily made to follow angular conveyor paths as when the conveyor passes from floor to floor in a building.

Other objects and advantages of the invention will become apparent from the following description of a preferred form, reference being had to the accompanying drawings in which—

Fig. 1 is a perspective view of a conveyor guard embodying the present invention; Fig. 2 is a section on line 2—2 of Fig. 1; Fig. 3 is a section on line 3—3 of Fig. 2; Fig. 4 is a fragmentary detail view of one form of basket reinforcement; and Fig. 5 is a fragmentary detail view of one form of basket fastening element, the parts being shown in dotted lines in the position assumed when the conveyor is inclined.

2

Referring to the drawings and particularly to Fig. 1, the guard is shown in connection with a conveyor of the mono-rail type comprising an I-beam 10 fixed to the ceiling of a building in any suitable manner by fastening devices which form no part of the present invention and hence are not disclosed. In the common installation of this character, articles are carried suspended from the lower flanges of the I-beam section usually by spaced rollers, one on each side of the I-beam web. It is, therefore, necessary to maintain the lower flanges completely unobstructed so that all supporting elements for the conveyor guard must be fastened to the top flange of the beam 10.

The conveyor guard itself comprises a continuous basket 12 formed as a channel of expanded metal or other material sufficiently heavy to support any object that may be carried by the conveyor if such objects should become accidentally dislodged during its travel. The basket 12 comprises, therefore, a plurality of end-to-end sections each having side walls 14 extending upwardly from a transverse lower floor 16. The side walls 14 may have their upper ends finished by wrapping around steel rods or similar devices or the walls themselves may be left without reinforcement at the top. It is preferred to make the floor and both side walls of the basket from a single piece of material and longitudinal rigidity for the structure is gained by forming the bend between a wall and the floor as indicated in Fig. 4. It will be noted that the material of the floor is first formed downwardly as at 17 and then bent sharply upwardly to form the side wall 14, which later lies closely against the down-turned portion 17. The reverse bend thus formed results in a structure which is highly rigid.

If additional strength against bending is required for the floor, cross braces 18 in the form of U-shaped rods may be provided at intervals in the length of the conveyor guard, such rods being fixed in place in any suitable manner as by small U bolts 20.

The basket is suspended from the rail 10 by rigid hanger members 22, welded or otherwise fixed to a connecting top cross piece 24. The suspending or hanger members 22 may conveniently be formed of sections of angle iron, while the cross piece 24 is preferably of a channel section although an angle section may be used if its strength is sufficient. The cross piece 24 of the hanger is provided approximately midway of its length with a T-shaped bracket 26 fixed to the web of the channel 24 by bolts 28.

The central leg of the T-shaped piece 26 extends, therefore, approximately at right angles to the web of channel 24 and is adapted to be received between rail clamping members 30 at each side. The clamping members 30 are held against the central extension of the T-shaped member 26 by a bolt 32. The T-shaped member may, if desired, be replaced by a single flat metal piece welded at right angles to the web of channel 24. It will thus be seen that when bolt 32 is drawn up by means of its cooperating nut, the top flange of rail 10 is clamped firmly between members 30 and the hanger elements are all fixed rigidly with respect to the rail but are easily demountable in the event that it becomes necessary to remove the guard for any reason.

As indicated in Fig. 3, the T-shaped connecting member 26 permits the conveyor guard to follow changes in the angular disposition of the rail as when the rail is bent upwardly or downwardly to pass between floors of a building. It is merely necessary to swing the conveyor guard supporting structure around bolt 32 to provide for such angular changes. Once the fastening elements are tightened, the structure becomes sufficiently rigid for complete protection.

The basket 12 is preferably fastened to the depending side angle members 22 as by separable fastening elements such as by a bolt 29 carrying a nut 42 overlying a plate 44 which serves to clamp the material of the basket side wall 14 against the upright hanger member 22. Plate 44 may be made of any desired extent, although it is usually sufficient that its length be made equal to two or three times the slit length of the expanded metal of which basket 12 is formed.

The adjacent ends of the sections of the basket 12 may be fixed together by simple spanning tie plates 50 bolted to each end of adjacent sections. If desired, the plates 50 may extend only adjacent the side walls 14 of the basket, or they may also be made continuous across the bottom 16. It will be apparent that simple rectangular plates 50 may be used where there is no change in the angular disposition of the conveyor, but that triangular plates will become necessary if an up or down turn is encountered between basket sections. Since the plates are simple sheet metal elements, such changes may be readily made by any mechanician.

While the invention has been shown in connection with a particular form and disposition of the parts, it should be appreciated that numerous modifications and changes may be made therein without departing from the spirit of the appended claims.

What we claim is:

1. A guard for a monorail trolley system or the like over which articles are carried in a suspended condition comprising, a plurality of end-to-end guard sections, hanger bars, means including separable fasteners to attach said hanger bars to the monorail, separable fastening means to attach said guard sections to said hanger bars, joining plates between said sections, and other separable fastening means to attach

said joining plates in position, whereby said guard may be removed from association with said monorail and said sections from each other by removal of said several separable fasteners.

2. A guard in accordance with claim 1 in which said end-to-end sections are formed of expanded metal through which separable fasteners pass.

3. A guard in accordance with claim 1 in which the means to attach said hanger bars to the monorail includes engaging clamping members, and a part carried by said hanger bar and received between said clamping members and adapted for swinging adjustment relative thereto.

4. A guard for a monorail trolley system or the like as described including a plurality of end-to-end basket sections formed of expanded metal or the like, said sections each having a bottom, and upstanding side walls connected to the bottom and continuous therewith, the connection between the sides and bottom comprising a downturned section immediately adjacent an upturned side wall whereby longitudinal stiffness is imparted to the basket section.

5. A guard for a monorail trolley system or the like including a monorail support and means for suspending articles from the support rail while they are conveyed therealong, which comprises a plurality of basket sections having a bottom and side walls formed of one continuous piece of mesh material, joining plates separably connecting the basket sections end-to-end to form a continuous trough beneath the monorail, and U-shaped hanger bars detachably mounted upon the monorail and attached to opposite sides of a basket section.

6. A guard for a monorail trolley system or the like including a monorail support and means for suspending articles from the support rail while they are conveyed therealong, which comprises a plurality of basket sections having a bottom and side walls formed of one continuous piece of expanded metal or the like, a reinforcing vertically aligned ridge at the juncture of each side wall with the bottom of the basket section formed by folding the mesh material back upon itself, joining plates separably connecting the basket sections end-to-end to form a continuous trough beneath the monorail, U-shaped hanger bars detachably connected to either side of a basket section, and means to attach the hanger bars to the support rail to permit swinging adjustment of the bars.
